UNITED STATES PATENT OFFICE.

FRANK W. HUBBARD, OF ERIE, PENNSYLVANIA, ASSIGNOR TO REED MANUFACTURING COMPANY, OF ERIE, PENNSYLVANIA, A CORPORATION.

VICE.

No. 903,137.

Specification of Letters Patent.

Patented Nov. 3, 1908.

Application filed June 9, 1905. Serial No. 264,487.

To all whom it may concern:

Be it known that I, FRANK W. HUBBARD, a citizen of the United States, residing at Erie, in the county of Erie and State of Pennsylvania, have invented new and useful Improvements in Vises, of which the following is a specification.

This invention relates to vises and consists in certain improvements in the construction thereof as will be hereinafter fully described and pointed out in the claims.

More particularly the invention relates to that type of vises wherein the vise jaws are swiveled on a base, the jaws and top to be turned to different angles and locked at the various angles to which they may be turned.

Heretofore vises of this character have been made wherein the base is provided with a circumferential groove, the walls of the groove being parallel with the axis of the base, and the bottom of the groove extending outwardly forming square shoulders with which a square headed bolt may engage. This construction involves two defects. One relates largely to the manner of manufacture. It is difficult to get at any imperfections in the castings in the undercut portion of the groove and as a result most vises so constructed have the groove machined, thus very largely increasing the expense of manufacture. A second difficulty arises from the fact that the square headed bolt does not engage the surfaces of the groove with sufficient firmness to readily lock the vise in an adjusted position. In this invention these difficulties are obviated, the invention being shown in the accompanying drawings as follows:

Figure 1 shows a plan view of the base. Fig. 2, a section on the line 2—2 in Fig. 3. Fig. 3, a section on the line 3—3 in Fig. 2. Fig. 4, a detailed view of the bolt head.

A marks the vise base and B what is ordinarily termed the fixed jaw; C, the movable jaw. The movable jaw is arranged to slide in the fixed jaw and is operated by the screw D operating with the nut E in the usual manner. A swivel bolt F extends through the center of the base into the jaw B and 50 swivels the jaw on the base. A groove a

having a curve with the axis of the vise as a center and preferably forming a complete annulus is arranged in the top of the base. This groove is dove-tailed shape in cross section, that is it has sides slanting to make a contracted opening to the groove. At the same time there is no decided shoulder which obstructs the ready introduction of a tool to remove any obstruction there may be in the groove. This construction of the groove also makes a simpler one to cast than the groove having the square undercut referred to.

A bolt G is provided with the head g. The head g is beveled to fit the sides of the groove a. The bolt extends through the opening b in the jaw and the nut H is arranged on the top of the bolt which, by means of the handle h, may be turned to operate the screw, thus drawing the head g into engagement with the sides of the groove a and clamping the vise. The bevel or wedge shaped construction of the head so increases the power of the clamping device that the vise may be readily set so as to prevent jarring loose. The wedge shape also facilitates the manufacture in the manner heretofore described.

What I claim as new is:

1. In a vise, the combination of a base member; a jaw member swiveled on the base, one of said members having a groove dove-tail shaped in cross section and extending in a curve with the axis of the vise as a center; a bolt having a connecting part arranged in the groove and engaging the sides thereof; and means for straining the bolt to clamp the base and jaw members together. 80

2. In a vise, the combination of a base member; a jaw member swiveled on the base, one of said members having a groove with an undercut and extending in a curve with the axis of the vise as a center; a bolt having a beveled connecting part arranged in the groove and engaging the sides thereof; and means for straining the bolt to clamp the base and jaw members together. 90

3. In a vise, the combination of a base member; a jaw member swiveled on the base, one of said members having a groove dove-tail shaped in cross section and extending in 100

a curve with the axis of the vise as a center; a bolt having a connecting part beveled to conform to the shape of the groove arranged in the groove and engaging the sides thereof; and means for straining the bolt to clamp the base and jaw members together.

5 In testimony whereof I have hereunto set

my hand in the presence of two subscribing witnesses.

FRANK W. HUBBARD.
